UNITED STATES PATENT OFFICE.

ROBERT L. LYONS, OF WALTHAM, MASSACHUSETTS, ASSIGNOR TO FREDERICK OSANN COMPANY, OF NEW YORK, N. Y., A CORPORATION OF NEW YORK.

BUTTON CLAMP.

Application filed March 9, 1925. Serial No. 14,108.

This invention relates to clamps for holding buttons and the like in position relative to attaching instrumentalities during the attaching of buttons to the work. Such clamps commonly comprise a plurality of pivotally mounted gripping jaws resiliently pressed toward each other and between which the buttons are placed. A stop adjustable in accordance with the size of the button which it is desired to sew may be employed to limit the closing movement of the jaws to a position slightly closer than when the jaws are in engagement with the button. This permits the insertion of the button by forcing it against and between the partly opened jaws, the jaw-closing spring or springs yielding to permit the necessary further separation of the jaws to permit the button to pass therebetween. In order, however, that the jaws may securely hold the buttons, they must engage the button edges at points less than 180° apart about its edge, the engaging portions when a button is in position being thus spaced from each other less than the diameter of the button and angularly disposed relatively to each other. As the buttons are inserted edgewise the pair of jaws between which it is passed must be separated at their outer edges the full diameter of the button during the insertion thereof. The outer edges of the button engaging faces of the jaws are thus engaged by the button initially at points at one side of a diameter where the tangents to the button edge are far from parallel and thus in a disadvantageous relation for wedging the jaws apart against the relatively heavy tension of the jaw closing spring. Moreover, due to the necessity of using relatively narrow jaws in order to properly engage the smaller sized buttons, they present relatively sharp edges to the button which is being forced therebetween. There is thus a tendency for these jaw edges to dig into the edge of the button rather than to separate to permit the button to pass therebetween. This digging in increases the pressure which it is necessary to exert to push the button into position.

One of the objects of this invention is to provide a construction whereby the insertion of the button is made relatively easy, thus relieving the operator from considerable physical effort and increasing the speed with which the buttons may be handled. This is done according to the present invention by

providing a lost motion connection between the jaws and their spring closing mechanism, this lost motion being normally taken up by a spring of less strength than the spring closing mechanism and being of sufficient amplitude to permit the jaws to be opened initially by a comparatively light pressure of the button against the jaws until they are so far opened that the jaw edges engage portions of the button edge nearer diametrically opposite to each other, and are thus disposed at a much more favorable wedge angle to engage the jaws and open them against the pressure of the main closing spring mechanism.

A further object of this invention is to provide a construction of the jaws which will automatically accommodate itself to buttons of different shapes.

While the invention is applicable to button clamps of various forms, for illustration it will be shown in connection with a button clamp of the type disclosed and claimed in my Patent 1,645,587, granted October 18, 1927, for button clamps.

Referring to the drawings,

Figure 1 is a fragmentary elevation partly broken away of a button sewing machine employing a button clamp constructed according to this invention.

Figures 2 and 3 are fragmentary front elevations showing buttons of different shapes in position between the button clamp jaws.

Figures 4 and 5 are diagrammatic views showing for different size buttons the engagement between certain of the jaws and the button edge as the button is being inserted into the clamp.

Figure 6 is a front elevation of the button clamp.

Figure 7 is a top plan view thereof.

Figure 8 is an inverted plan view thereof.

Figure 9 is a disassembled fragmentary perspective of certain jaw elements.

Figure 10 is a fragmentary perspective of other jaw elements.

Figure 11 is a fragmentary perspective showing the parts illustrated in Figures 9 and 10 assembled.

Referring first to Figure 1, 1 indicates a portion of a sewing machine frame having a work plate 2 beneath which is located a looper 3 rotatable with the looper shaft 4. Above the work table 2 is a head 5 carrying other sewing instrumentalities including a needle

bar 6 and a needle 7. The head 5 is carried at the end of an arm 8 overhanging the frame portion 1 in the usual manner. A button clamp comprising a frame 10 on which are mounted the button engaging jaws, as will later appear, is fixed to an angle shaped arm 11 pivoted at its lower end as at 12, this frame normally being rocked downwardly to permit the button clamping jaws to engage the work, but being raised upwardly at certain times, as by means of a chain 13, having its lower end fixed to the frame 10, as at 14, and pulled upwardly by any suitable raising mechanism in the usual manner. Commonly three button clamping jaws are employed and the clamp herein shown and described is so provided. Of these jaws, two comprise shank portions or members 15 pivoted at their rear ends as at 16 to the frame 10 and extending along the lower side thereof slightly beyond the front portion of the frame where they are shown upwardly turned at angles to their rear portions as at 18. As shown in detail in Figures 10 and 11 each of these upturned portions has an opening 19 in which is threaded the inner end of a screw 20 which passes loosely through a perforation 21 in the upper end of a button engaging member 22 which projects downwardly, the lower ends of these members 22 being turned forwardly and then toward each other where they are formed with button-engaging faces 25. The enlarged perforations 21 through these members provide a lost motion connection between these members and their respective shank portions which is limited in extent by a pin 27 projecting from each of the portions 18 and engaging in a slot 28 in each of the members 22. This lost motion is normally taken up in one direction by means of springs 30, each of which has a hooked lower end 31 engaging over the outer edge of a member 22 and the upper end of which is fixed as by means of screws 40 to the corresponding shank member 15. The shank members 15 are normally urged toward each other by a comparatively heavy spring. As herein shown this spring comprises a looped wire 45 extending about the outer edge of the frame 10 and having its forward ends inwardly turned as at 46 and engaging in perforations 47 in the outer edges of the shank members. The swinging motion of the shank members 15 toward each other is limited by a suitable adjustable stop. As herein shown this stop comprises a block 50 fixed to one of the shank members 15 which is engaged by the end of a screw 51 threaded through the other shank member 15, this screw being provided at its outer end with a knurled head 52 by which it may be turned. A nut 53 and a lock washer 54 on this screw 51 may be employed to hold it in adjusted position. This screw should be so adjusted that the lower ends of the jaw members 22 are limited in their closing movement to

positions spaced apart only slightly less than the diameter of the button to be engaged so that the jaws are not required to be opened far in order that the button may be inserted. It will be noted that both the springs 45 and 30 act to bring the button-engaging faces 25 toward each other as far as is permitted by the adjustable stop screw 51 and the pins 27 engaging the ends of the slots 28 of the members 22.

In order to hold the button from being pulled out between the button-engaging faces 25, these faces, as disclosed more particularly in Figures 4 and 5, are not parallel to each other, their outer edges being closer together than their inner edges and when engaging the button they engage forwardly of a diametrical line thereacross. It will be seen by reference to these figures, that when the button edge is presented to the members 22, which are spaced the proper distance to permit the faces 25 to engage the button edge under the required spring pressure when the button is in position, the comparatively sharp outer edges 60 engage the button edge as at the points *a* and *b* where the tangents *c*, *d* and *e*, *f* to the button edge are far from parallel to each other, consequently pressure of the button in the direction of the arrow *X* of Figure 4 to force the button-engaging faces apart sufficiently to permit the button to pass therebetween acts at a very unfavorable wedging angle. Consequently if the pressure holding these button-engaging faces toward each other is strong, the resistance to the insertion of the button is very considerable. By the lost motion connections between the members 22 and the shank members 15, the necessity of initially opening the jaws to permit the button to pass against the relatively heavy tension of the spring 45 is removed, it being only necessary for the initial opening movement to act against the relatively light springs 30 which yield as the pressure is applied to the button until the pins 27 engage the opposite ends of the slots 28. By this time, however, the button is so far moved between the jaws that the edges thereof engage the button edge much nearer diametrically opposite to each other, whereupon the tangents at the points of contact between the jaws and the button as the lines *m*, *n* and *o*, *p* are much nearer parallel to each other than the tangent lines *c*, *d* and *e*, *f*. These tangents *m*, *n* and *o*, *p* are thus at a much more favorable wedging angle relative to the clamping jaws and hence pressure exerted on the button is more effective to open these jaws under the relatively heavy tension exerted by the spring 45. It is therefore necessary to exert much less pressure on the button than when the button was originally presented to the jaws. It is thus considerably easier for the operator to insert the buttons in position where it is unnecessary to oppose the action of the relatively heavy

spring 45 during the initial opening movement of the jaws.

The advantage gained by this construction is, of course, more pronounced with small buttons than with large buttons as is clearly evident by reference to Figures 4 and 5 in which it is seen that the tangent at the initial point of contact between the clamp edge and the button is more favorable with the large buttons than with the small buttons. The action is, however, of material help to the insertion of large buttons.

Cooperating with the pair of jaws thus described is a third jaw 70 as shown in the patent above referred to, this jaw being carried by a plate 71 slidable lengthwise of the frame 10 therebeneath and connected through pin and slot connections 72 with the shank members 15 in order that simultaneous opening 20 and closing movement of the three jaws during all except the taking up of the lost motion connection between the shank members and the members 22 is insured.

Not only is a button clamp required to take buttons of different sizes, but the buttons commonly vary in thickness and in cross sectional contour, certain of the buttons being much thicker at their centers than at their edges and other buttons being of more nearly uniform thickness. In order to provide for handling buttons of different thicknesses and cross sectional contours, the jaw elements 22 may each be provided with spring elements 75, each having an upwardly turned end 76 projecting inwardly toward the other jaw element 22 and toward the center of a button engaged by these jaws beyond the button-engaging face 25, these ends forming lips adapted to overlie the upper faces of the buttons inserted between the jaws. These spring elements 75 may be formed to overlie the members 22 and extend upwardly against their forward faces. In order to permit an adjustment thereof relative to the members 22 to provide for varying thicknesses of buttons, they are shown as connected to these members 22 by means such as screws 77 passing through perforations 78 of larger diameter than the shanks of the screw, the inner ends of the screws being threaded into the members 22. There is also shown a pin 79 extending outwardly from the forward face of each of the members 22 through an enlarged perforation 80 in the spring element 75 so as to limit the extent of adjusting bodily movement between the spring element and the member 22. The upwardly turned ends 76 of these spring elements engage above the buttons positioned between the jaws being vertically adjustable relative to the member 20 to take buttons of varying thicknesses as shown in Figures 2 and 3. Since they are upwardly turned at their inner ends their button facing portions are upwardly inclined so that they may engage with buttons of greater

thickness at their centers than at their edges, as is illustrated in Figure 3, though no harm is done in case buttons of substantially uniform thickness are used, in which case the inner ends of these spring elements do not 70 contact therewith. As shown in Figure 2 the button is so thin that the springs 75 can not actually contact therewith, but they do come sufficiently close thereto to prevent such excessive movement of the button between the 75 clamping jaws as might be liable to affect its position with reference to the sewing instrumentalities during the attaching of the button to the work. In Figure 3 they are shown as engaging a larger button having a thick 80 central portion. This manner of mounting the springs also permits the projection of the lip portions beyond the jaw ends to be adjusted, buttons of smaller sizes requiring less projection than those of larger sizes. Buttons of small size require relatively slight projection since otherwise the lips would be liable to cover over the sewing holes in the button, while a slight projection would be insufficient to retain large buttons in the clamp against 85 the pull of the thread as it is drawn up by the machine take up.

Having thus described certain embodiments of this invention it should be evident to those skilled in the art that various changes 95 and modifications might be made therein without departing from its spirit or scope as defined by the appended claims.

I claim:

1. A device of the class described comprising a plurality of button-engaging jaws, means for pressing said jaws toward each other to clamp a button therebetween, and a lost motion connection between certain of said jaws and means acting to permit said jaws to separate to a limited extent without affecting said pressing means.

2. A device of the class described comprising a plurality of button-engaging jaws, means for pressing said jaws toward each other to clamp a button therebetween, means for limiting the closing movement of said jaws to an adjustable extent, and means for permitting a limited separation of said jaws from said closing limit without affecting said 115 pressing means.

3. A device of the class described comprising a plurality of button engaging jaws, means including a plurality of springs of different strengths for pressing said jaws toward each other, and means for permitting a limited opening movement of said jaws against the pressure of the weaker of said springs and further opening of said jaws against the pressure of the stronger of said 125 springs.

4. A device of the class described comprising a plurality of button-engaging jaws, certain of said jaws comprising two parts having a lost motion connection with each 130

other, a spring for pressing said parts to one limit of said lost motion and a spring for pressing said jaws toward each other.

5. A device of the class described comprising a plurality of button-engaging jaws, certain of said jaws comprising two parts having a lost motion connection with each other, a spring for pressing said parts to one limit of said lost motion and a spring for 10 pressing said jaws toward each other, said last mentioned spring being of the greater strength.

6. A device of the class described comprising a plurality of button-engaging jaws, 15 certain of said jaws comprising a shank portion and a button-engaging portion having a lost motion connection with one end of said shank portion, a pivotal mounting for the opposite end of said shank portion, means 20 engaging the shank portions of certain of said jaws for closing all of said jaws toward each other, a stop for adjustably limiting the extent of closing movement of said shank members, and springs for taking up the lost 25 motions of said connections in a direction to close said jaws.

7. A device of the class described comprising a plurality of button-engaging jaws, certain of said jaws comprising a shank portion, 30 a button-engaging portion having a lost motion connection with one end of said shank portion, a pivotal mounting for the opposite end of said shank portion, means engaging the shank portions of certain of 35 said jaws for closing all of said jaws toward each other, a stop for adjustably limiting the extent of closing movement of said shank members, and springs for taking up the lost 40 motions of said connections in a direction to close said jaws, said springs being of less strength than said closing means whereby opening pressure exerted on said jaws takes up the lost motion of said connections in opposition to said springs before affecting said 45 closing means.

8. A device of the class described comprising a frame, a pair of jaws each comprising a shank portion pivoted at its rear end to said frame, a button-engaging member pivoted to the forward end of each of said shank portions, and having a button-engaging face, means for limiting the extent of movement between said shank portions and member, a relatively light spring for pressing 50 said members toward each other about their pivotal connections with said shank portions, and a relatively heavy spring for pressing said shank portions in a direction to close said jaws.

60 9. A device of the class described comprising a frame, a pair of jaws each comprising a shank portion pivoted at its rear end to said frame, a button-engaging member pivoted to the forward end of each of said shank 65 portions, and having a button-engaging face,

means for limiting the extent of movement between said shank portions and member, a relatively light spring for pressing said members toward each other about their pivotal connections with said shank portions, a relatively heavy spring for pressing said shank portions in a direction to close said jaws, and an adjustable stop for limiting the extent of jaw closing movement of said shank portions.

75 10. A device of the class described comprising a frame, a pair of jaws each comprising a shank portion pivoted at its rear end to said frame, a button-engaging member pivoted to the forward end of each of said shank portions, and having a button-engaging face, means for limiting the extent of movement between said shank portions and member, a relatively light spring for pressing said members toward each other about their pivotal connections with said shank portions, a relatively heavy spring for pressing said shank portions in a direction to close said jaws, and a third jaw movable 80 toward and from said pair of jaws as said shank portions are given closing and opening movements, respectively.

85 11. A device of the class described comprising a frame, a pair of jaws each comprising a shank portion pivoted at its rear end to said frame, a button-engaging member pivoted to the forward end of each of said shank portions, and having a button-engaging face, means for limiting the extent of movement between said shank portions and members, a relatively light spring for pressing said members toward each other about their pivotal connections with said shank portions, a relatively heavy spring for pressing said shank portions in a direction to close said jaws, an 90 adjustable stop for limiting the extent of jaw-closing movement of said shank portions, and a third jaw movable toward and from said pair of jaws as said shank portions are given closing and opening movements, respectively.

100 12. A device of the class described comprising a frame, a pair of jaws each comprising a shank portion pivoted at one end to said frame and extending forwardly, the forward ends of each of said shank portions being turned at an angle to the remaining portion, button-engaging members pivoted at their upper ends to said turned ends and having button-engaging faces at their lower ends, means for limiting the extent of pivotal movement of said members relative to said shank portions, springs for yieldingly holding said members to their limits of pivotal motion toward each other, resilient means of greater strength than said springs acting on said 105 shank portions to swing them toward each other, and an adjustable stop to limit the extent of such swinging.

125 13. A device of the class described comprising a frame, a pair of jaws each comprising a 130

shank portion pivoted at one end to said frame and extending forwardly, the forward ends of said shank portions being turned upwardly, button-engaging members pivoted at their 5 upper ends to said upwardly turned ends and having button-engaging faces at their lower ends, means for limiting the extent of pivotal movement of said members relative to said shank portions, springs for yieldingly holding 10 said members to their limits of pivotal motion toward each other, resilient means of greater strength than said springs acting on said shank portions to swing them toward each other, an adjustable stop to limit the extent 15 of such swinging, and a third jaw movable to approach said button-engaging faces as said shank portions are swung toward each other and to recede from said faces as said shank portions are swung away from each other.

20 14. A button clamp comprising a pair of button-engaging jaws and a leaf spring carried on the upper face of each of said jaws and projecting toward the other jaw in an upwardly inclined direction above a button held 25 between said jaws.

15. A button clamp comprising a plurality of button-engaging jaws, and a leaf spring carried by one of said jaws and having an upwardly inclined end projecting toward the 30 other jaw over a button positioned between said jaws.

16. A button clamp comprising a plurality of button-engaging jaws, and a leaf spring carried by one of said jaws and having an up-

wardly inclined end projecting toward the 35 other jaw over a button positioned between said jaws, said spring being adjustable on said jaw to conform to buttons of different sizes and contours.

17. In a button clamp, a button engaging 40 jaw having a spring lip projecting therefrom in position to extend over a button engaged by said jaw, said lip having its button-facing portion inclined upwardly away from said jaw toward the center of a button engaged 45 thereby.

18. In a button clamp, a button engaging jaw having a lip projecting therefrom in position to extend over a button engaged by said 50 jaw, and means by which the amount of projection of said lip from said jaw may be adjusted.

19. In a button clamp, a button engaging jaw, a lip member overlying said jaw and projecting over a button engaged by said jaw, 55 and means whereby said lip member may be positively adjusted bodily vertically with relation to said jaw.

20. In a button clamp, a button engaging jaw, a lip member overlying said jaw and 60 projecting over a button engaged by said jaw and means whereby the extent of projection and the vertical position of said lip member relative to said jaw may be adjusted.

In testimony whereof I have affixed my 65 signature.

ROBERT L. LYONS.
